UNITED STATES PATENT OFFICE.

ROBERT S. ISARD, OF HUDSON, OHIO.

FIRE-ESCAPE.

SPECIFICATION forming part of Letters Patent No. 291,014, dated December 25, 1883.

Application filed April 11, 1883. (No model.)

To all whom it may concern:

Be it known that I, ROBERT S. ISARD, of Hudson, county of Summit, and State of Ohio, have invented a new and Improved Fire-Escape; and I do hereby declare that the following is a full, clear, and exact description of the same, reference being made to the accompanying drawing, and to letters of reference marked thereon.

10 My invention relates to certain new and useful improvements in fire-escapes, and has for its object the provision of a device by means of which any number of windows or like openings in a building may be made a safe means 15 of egress for escaping from a burning structure and reaching the ground in safety. My intention is to have a fire-escape so constructed and arranged that it may be moved from one window to another, and between the extreme 20 ends of buildings, and for convenience in bringing the device around corners or like obstacles, and for raising the lower portion of the ladder, so that it may pass over obstructions beneath it. In order to provide for the moving 25 of the ladder from place to place, a suitable tramway or rails are provided at or near the eaves of the roof, from which the ladder is suspended on trucks or rollers, so that it may be drawn to the right or left at will and 30 brought in front of any window or other opening desired.

In the drawing is shown a vertical elevation of a portion of a building having my improved fire-escape in position.

35 A is the building proper, to the eaves A' of which are attached hangers or brackets B, of any suitable form to accommodate them to the style of the roof. These hangers are held and prevented from spreading by the rods b, 40 having nuts both within and without the hanger at a. To these hangers are attached the rails C, having the part upon which the trucks run, c, lower than the outside, so that they cannot leave their track.

45 D are the trucks, having jointed hangers de-

pending from their axles, and holding the upper section of the extensible jointed ladder E. In order to give flexibility, the ladder has the hinged or jointed parts e e' f, constructed as plainly shown in the drawing, so that it can 50 bend or fold as it passes around a curve like that at D', which is shortened between the points e e' to avoid a right angle. A weight, F, holds the lower section of the ladder up away from interference and out of the way until it is lowered at will by drawing down the cord or cable F', and at any time by releasing the cable the section will be lifted to pass over an "ell" or any similar obstruction. Cables G G lead from the right and left, so that by 55 taking hold of them the ladder can be moved on the rails to any desired locality where it is necessary to bring it. It will readily be seen how quickly this can be done and how any tier of windows can be reached at once. All 60 parts of the device are of iron and steel, so that 65 heat and flames will not render it useless.

Having thus described my invention, what I claim as new, and desire to secure by Letters Patent, is—

70 1. In a fire-escape having extensible jointed ladder, the hangers B, rails C, and trucks D, all constructed and arranged substantially as and for the purposes set forth and described.

2. In a fire-escape, the extensible jointed 75 ladders E E', arranged to operate in the manner and for the purposes set forth and described.

3. An extensible jointed ladder traveling upon trucks and rails and suspended from a 80 building, with suitable means for moving the same, so that the various openings or exits may be reached, substantially as set forth.

This specification signed and witnessed this 9th day of February, 1883.

ROBERT S. ISARD.
